UNITED STATES PATENT OFFICE.

ELMER E. WOLF, OF SPRINGFIELD, OHIO, ASSIGNOR, BY MESNE ASSIGNMENTS, TO
EMPIRE VOTING MACHINE COMPANY, OF ROCHESTER, NEW YORK, A CORPORATION
OF NEW YORK.

VOTING-MACHINE.

942,991.

Specification of Letters Patent. Patented Dec. 14, 1909.

Application filed August 30, 1901. Serial No. 73,856.

To all whom it may concern:

- Be it known that I, ELMER E. WOLF, a citizen of the United States, residing at Springfield, in the county of Clark and State of Ohio, have invented certain new and useful Improvements in Voting-Machines, of which the following is a specification, reference being had therein to the accompanying drawings.
- 10 This invention relates to voting machines, and has for its object to provide a properly safeguarded apparatus whereby the votes of the electors may be automatically registered or counted.
- 15 More specifically, the object of the invention is to provide an apparatus whereby a voter may either vote for all of the candidates of a given party by a single operation of the apparatus or may vote for any one 20 candidate for any one office, duly nominated by any party, and for one such candidate only. Provision is made for enabling the voter to vote for any independent candidate not regularly nominated for any office.
- 25 A further object of the invention is to provide for the voting of what is known as a "split ticket" in the case of presidential electors, whereby the voter may, at his option, vote for a portion of the electors nominated by any one party and for such other electors as he may choose.

30 35 40 45 50 55 60 65 70 75 80 85 90 95 100 105

A further object of the invention is to provide for a referendum vote, or, in other words, the voting "yes" or "no" on any proposition or propositions submitted to the electors.

My invention has for a further object to provide for the voting of those voters who have only a limited suffrage, or, in other words, who are only allowed to vote for certain officers, and not for all of the officers to be elected, as, for instance, in the case of those localities where women are allowed to vote for school officers only. In all cases provision is made to prevent the voter from casting more votes or voting for more candidates than he is entitled to vote for.

To these and other ends the invention consists in certain novel features which I will now proceed to describe and will then particularly point out in the claims.

In the accompanying drawings, Figures 1 and 1^a, the latter of which is a continuation of the former, show a front elevation of the

machine embodying my invention in one form; Figs. 2 and 2^a, the latter of which is a continuation of the former, show an end elevation of the machine; Figs. 3 and 3^a, the latter of which is a continuation of the former, show a view similar to Figs. 2 and 2^a, but with the end of the casing removed; Figs. 4 and 4^a, the latter of which is a continuation of the former, show a vertical section, taken on the line A B of Fig. 1, and looking in the direction of the arrows; Fig. 5 is a sectional view of a portion of the apparatus, taken on the line C D of Fig. 3, and looking in the direction of the arrows or from the back of the machine; Fig. 6 is a plan section of a portion of the apparatus, taken on the line E F of Fig. 4; Fig. 7 is a detail sectional view, taken on the line G H of Fig. 5; Fig. 8 is a detail perspective view of a portion of the mechanism viewed from the rear of the machine; Fig. 9 is a rear elevation of a part of the lower portion of the apparatus; Fig. 10 is an enlarged vertical section of the lower portion of the apparatus; Fig. 11 is a plan view of a portion of the same; Fig. 12 is a detail sectional view, taken on the line I J of Fig. 11; Fig. 13 is a detail perspective view of one of the bell mechanisms; Fig. 14 is a detail sectional view of portions of the registering devices and their coöperating parts; Fig. 15 is a plan view, the casing being in section, of one end of the upper part of the apparatus; Fig. 16 is a detail sectional view, taken on the line K L of Fig. 10; Fig. 17 is a detail view of a part of the apparatus, viewed from the rear and illustrating the relative arrangement of the locking rods of one group of candidates; Fig. 18 is a perspective view of one of the registers; Fig. 19 is a similar view with portions of the mechanisms removed; Fig. 20 is a detail view, partly in section, of one of the register wheels; Figs. 21 and 22 are, respectively, an end view and a rear elevation of the locking devices whereby the mechanisms for recording the independent votes are secured in position in the machine; Fig. 23 is a detail plan view of a portion of the mechanism by which the main operating lever is connected with the mechanism of the machine; Fig. 24 is a perspective view, illustrating the connections of the limited suffrage lever with the mechanism operated

thereby; and Fig. 25 is a vertical sectional view of one of the casings.

Referring first to the general arrangement of the machine, it will be observed that it comprises a suitable inclosing casting 1, to be hereinafter more particularly described, the face or front of said casting being provided with push buttons arranged in both horizontal and vertical rows. 5 Any desired number of these buttons may be employed, according to the number of offices to be filled and the number of candidates for each office. Each vertical row of push buttons is assigned to the several candidates for one given office, each candidate having a separate push button, while each horizontal row is assigned to the several candidates for the different offices of the same party. Each push button is provided 10 with a separate coöperating register, and each vertical steering of push buttons is so combined and arranged that, when any one of the buttons of the vertical row has been operated, it becomes impossible to operate any other one in that vertical row until the 15 machine has been re-set. Thus, under normal conditions, it is impossible for the voter to vote for more than one candidate for any given office.

I will first describe so much of the machine as relates to the operation of voting for a duly nominated candidate for a given office. The push button, which is indicated at 2, is provided with a shank or stem 3, which slides in a bearing 4 in the frame or casing of the machine, and is preferably provided at its inner end with a button or enlargement 5.

6 indicates a normally stationary shaft, 40 extending the length of the machine, and serving to support the various registers which coöperate with the corresponding horizontal line of push buttons, or, in other words, the registers for the several candidates of any one party. These registers 45 may be of any suitable construction, but I prefer the particular form shown, and which is illustrated in detail in Figs. 18 to 20 of the drawings. In this construction the shaft 6 is shown provided with a series of indicator wheels 7, each wheel being provided with a toothed actuating wheel 8 rotating in unison with it. Mounted to rotate on the shaft 6 is a sleeve 7^a, provided with an arm 50 8^a, which projects into the path of the inner end of the stem of the push button 2, so that, when this latter is pushed inward, the sleeve 7^a will be rotated or rocked on the shaft 6. This sleeve is provided with an arm 9, which 55 carries the actuating pawls for the indicator wheels. To this end it is provided with a pivot pin 10, on which is mounted a plate 11, having a spring 12, which forces the pawl fingers 13 toward the toothed actuating wheels 8. It will be observed that the

pawls 13 are set at different angles, as indicated in Fig. 7, and it will also be observed that each actuating wheel 8 is provided with a notch or recess 14. The arrangement is such that the pawl of the units wheel, when in contact with the periphery of said wheel, 70 will hold the other pawls out of contact with their actuating wheels. But when the pawl of the units wheel enters the notch 14, it moves toward the shaft 6 to an extent sufficient to permit the pawl of the next or tens wheel to engage with its actuating wheel, and, similarly, when these two pawls both enter the notches of their actuating wheels, 75 then the pawl of the hundreds wheel engages. The wheels are prevented from rotating backward by means of dogs 15, carried by arms 16, attached to stationary sleeves 17, said sleeves being held stationary by means of an arm 18, which extends upward from one of the sleeves 17 and is notched or recessed at its upper end, as shown at 19, to embrace a shaft 20, to be hereinafter referred to, and which extends the length of the machine above and parallel 80 with the shaft 6. The shaft 6 is provided with a shoulder 21, and each of the indicator wheels is provided with a pin 22, which is forced toward the shaft 6 by means of a spring 23, so that, while the indicator wheels 85 are free to turn on the shaft in the direction in which they are intended to move, they can all be quickly and readily set back to zero by turning the shaft 6 in the same direction.

The sleeve 7 is provided with an arm 24, and this arm is pivotally connected at 25 to a clip 26, secured to a rod 27. These rods, which are clearly shown in Fig. 8 of the drawings, are of inverted U-shape in form, 105 extending upward to the top of the machine, where they pass through a suitable guide support. This shape of the rods enables me to give to both arms thereof such a length below their guide support as to provide sufficient flexibility of their lower ends to permit of the connections and movements hereinafter referred to. In the present instance I have shown this guide support as consisting of a tubular rod or bar 28, extending the 110 length of the machine near the top thereof and apertured for the passage of the two members of each rod. The rods coöperating with the vertical series of push buttons form a group, and the construction is such that, 115 when one rod of a group is depressed, none of the other rods can be depressed, so that, when one push button of any vertical series has been operated, no other push button of that series can be operated until the machine 120 is re-set. The rods of each group are arranged side by side, as shown in Fig. 8, and in Fig. 17 I have illustrated the manner in which the various arms 24 may be modified 125 with relation to the sleeve 7, so as to permit 130

the push buttons and registers to be located in a vertical row, while the several rows of the group are offset relatively to each other.

Referring now particularly to the locking devices, which are best shown in Figs. 8 to 12 of the drawings, inclusive, it will be noted that the lower end of each rod is flattened, as indicated at 29, and this flattened portion terminates in a wedge-shaped portion 30, which in turn is provided with a reduced extension 31. 32 indicates a bed piece, extending across the machine from side to side at the bottom thereof, and having a longitudinal slot 33, into which the reduced extensions 31 extend. This bed piece is provided at the upper end of the slot 33 with a groove or race way 34. In this race way are located a plurality of balls or spheres 35. Mounted transversely in the bed piece 32 are a plurality of rods 36, one between each group of the rods 27. Each rod 36 passes through the race way 34 and is notched or recessed, as shown at 37, so that, when this notched portion of the rod coincides with the raceway or groove 34, the total length of said groove between any two of the bars 36 will be increased by the width of the notches 37. When the parts are in this position, if any one of the rods 27 is depressed, the balls 35 and the remaining rods will yield laterally sufficiently to permit the wedge-shaped part 30 of the rod which is depressed to pass down between the balls. The proportions are such, however, that when one of the rods has been depressed there is no further space in that particular group to permit the depression of any other one of the rods, and it therefore follows that, when any one push button of any vertical series has been operated, none of the other push buttons of that series can be operated until the machine has been re-set.

Each of the rods 36 is made in two parts, connected by a yoke 38, passing through the bed piece 32, which is apertured as shown at 39, for the free passage of the yoke. The rod 36 is adapted to slide longitudinally in an aperture 40 in the bed piece, and between the ends of the two sections of the rod 36 there is located in this aperture a ball 41. By moving the rod longitudinally, this ball may be brought into line with the groove or race way 34. Each yoke may be secured in position after adjustment by means of a clamp 38^a secured to the yoke and embracing a fixed pin 38^b projecting from the bed piece 32. Coöperating with the mechanism just described is a stop device, comprising a carriage 42, which is arranged to slide in a way 43 on the bed piece 32. In order to secure the carriage in any position in which it may be placed, the way 43 is dovetailed, as shown, and the body of the carriage which rests upon the top of the bed piece is provided with a corresponding dovetailed projection

44, which fits in the way 43. The central portion 45 of this dovetailed projection is separate and of less height than the remainder, as indicated in Figs. 9 and 10, and has secured to it an upright screw 46, which passes through a bearing sleeve 47 on the carriage 42, its projecting upper end receiving a threaded hand nut 48. The carriage is provided with a transverse split bearing 49, on the upper member of which the sleeve 47 is formed or mounted, and in this split bearing is mounted a shaft 50, which is adapted to rotate and move longitudinally in said bearing when the hand nut 48 is loosened, but which is clamped therein in an obvious manner when said hand nut is tightened. This operation of tightening the hand nut also clamps the carriage in the position to which it is adjusted by means of the movable portion 45 of the guiding projection. 75 The shaft 50 is provided at its front end with a stop arm 51, indicated in dotted lines in Fig. 9, which stop is adapted to be projected down into the slot 34 so as to lie in the path of the balls or spheres 35. For the purpose of conveniently operating the shaft 50, it is provided at its rear end with a suitable hand grasp 52.

Those portions of the mechanism last described constitute a provision whereby, when occasion occurs, the machine may be so adjusted as to permit the voting for a number of candidates for any one office, as, for instance, where the voter is entitled to vote for say three members of the legislature. 100 In the present instance I have shown the stop device as located at the extreme right hand of the machine, and, assuming that the machine is to be arranged to permit the voter to vote for three legislators, the machine is set for that purpose in the following manner. The three yokes 38, with their rods 36 at the right hand end of the machine, are moved back until the balls or spheres 41 are in line with the other balls or 110 spheres 35 in the groove 34. Any three plungers of the three right hand groups are then depressed, so that their broad portions 29 are in the groove 34. The carriage 42 is then moved up by first releasing the hand nut 48 and then turning the shaft 50, so as to withdraw the stop arm 51 from the slot 34, and then pulling back said shaft 50 until the stop arm and the hand grasp 32 will clear any obstacles which may be in 115 their path. When the carriage is brought approximately to the proper point the shaft 50 is again moved forward and the stop arm is turned down into the slot 34, whereupon the carriage is finally moved up into a position where the stop arm will contact with the ball or sphere 41 of the yoke at that end of the machine, and being pressed firmly against the same, the stop device is locked in position by tightening the hand nut 48. 130

The machine is then set for operation by withdrawing the locking rods, and it will be seen that, if the three vertical rows at the right hand of the machine be utilized for the purpose of voting for the legislative ticket, then the voter may operate any three of the push buttons of the said three vertical rows, but no more than three, since after three of the locking rods are depressed the extra space obtained has been exhausted and no more of the locking rods can be depressed.

While I have described the stop device as used in connection with the groups of locking rods at the extreme end of the machine, it will be seen that it may be similarly used at other portions of the machine by moving it to the place where it is needed, the locking rods yielding sufficiently to permit its insertion in the groove at any point.

In order to indicate to the voter that the vote cast by him for any given office has been registered by the machine, I employ in connection with the group of locking rods a visible signal. To this end the casing is provided with an opening 53 above each vertical series of push buttons, these openings being preferably closed by a piece of glass 54, or other suitable transparent material. Back of this sight opening is a plate 55, the upper portion of which is normally opposite the sight opening and is blank, while the lower portion thereof, which may be brought opposite the sight opening in the manner hereinafter described, has inscribed on it the word "vote", or some other suitable word to indicate that a vote has been cast. This plate is secured to an arm 56 on a sleeve 57, mounted on a rod or fixed shaft 58, supported by arms 59, which are secured to the tubular support 28 by clips 60. Each sleeve 57 is provided with rearwardly extending arms 61, which pass between the upper ends of the rods 27, as shown more particularly in Figs. 4 and 15, and these arms 61 carry a rod 62, which is located between the two branches or arms of the U-shaped locking rods 27, and which extends the length of one group of said rods. It will be seen that when any one push button of any vertical row has been operated the corresponding locking rod of that group will be depressed in the manner hereinbefore described, and the upper end of said locking rod will engage with the bar 62 and depress the same, thereby rocking the sleeve 57 and moving the plate 55 into a position such that the word inscribed on its lower portion will be visible through the sight opening 53, thus indicating to the voter the fact that his vote for that particular office has been registered by the machine. Since a similar mechanism is employed for each vertical row, the voter can tell by an inspection of the face of the machine what offices he has voted for. It

is also desirable that the officials in charge of the machine should be advised as soon as any vote for any candidate has been cast by the voter, and to this end I employ at the rear of the machine a similar sight opening 63, glazed, as indicated at 64, and opposite this opening I locate a plate 65 similar to the plate 55. This plate 65 is carried by an arm 66, secured on a rock shaft 67, extending the length of all of the groups of rods 27 and having its end bearings 68 supported by arms 69 from clips 70, secured on the tubular support 28. The rock shaft 67 is provided with a plurality of forwardly extending arms 71, corresponding in number with the groups of rods 27, each arm 71 extending between the rods of its group, as shown in Figs. 4 and 15, and underneath the rod 62 of said group. It will be therefore apparent that when any rod of any group is depressed by the casting of a vote the rod 62 of that group will be depressed and will operate the arm 71 and rock shaft 67, so as to cause the arm 66 to raise the plate 65 into a position where it will indicate to the official in charge the fact that a vote has been cast.

In addition to the mechanism just described, whereby provision is made for voting for individual regularly nominated candidates, I also provide means whereby the voter may, by a single operation, vote for all of the candidates nominated by any one party, or, in other words, may vote what is known as a straight ticket. This is accomplished by means of the shafts 20 hereinbefore referred to, and of which a number are employed equal to the number of shafts 6 which carry the registers. Each shaft 20 is located above and parallel with the corresponding shaft 6 and is supported in suitable bearings in partitions 72 and 73 near the ends of the machine. At a point adjacent to each registering mechanism on the corresponding shaft 6 there is secured on the shaft 20 a sleeve 74, provided with an arm 75, having a pin 76, which, in the normal position of the parts, as shown in Fig. 7, lies in front of and slightly below the upper end of the arm 8 of the registering mechanism. A rotary movement of the shaft 20 in the proper direction will cause said pin to engage the arm 8 and thereby operate the registering mechanism and locking mechanism, and this is true of all of the registering mechanisms upon the particular shaft 6 which co-operates with the particular shaft 20. In order to operate said shafts 20, I provide at the front of the machine a vertical series of levers 77, one for each shaft 20, each lever 77 terminating in a disk 78, pivoted at 79 in the frame of the machine and slotted as to its rear portion to receive the forward end of a link 80, which is pivoted to the disk between the walls of the

slot, as indicated at 81. This link 80 is itself slotted at its rear end, as indicated at 82, and this slotted portion passes between the arms 83 of a clip 84, secured on the corresponding shaft 20, a pin 85 passing through the arms 83 and through the slot 82 in the lever. The arrangement of the parts is such that in the normal position of the machine the pin 85 lies against the front or lower end of the slot 82. It will therefore be seen that if the lever 77 coöperating with any given shaft 20 be depressed the link 80 will operate on the pin 85 and clip 84 so as to rotate the shaft 20 in such a direction as to operate all of the counters upon the corresponding shaft 6, and consequently cause the machine to register a vote for each of the candidates of the particular party to whom that particular series of registers is assigned. It will be observed, however, that, owing to the slotted connection of the link 80 with the rock shaft, after said rock shaft has been operated once it cannot be operated again by moving the lever 77 until the machine has been re-set in the manner hereinafter described. It should also be noted in this connection that, when any one of the push buttons has been operated once, further operation of the said button will not affect the machine until after the re-setting thereof.

In order to prevent the use of the straight vote mechanism after one of the individual voting devices has been employed, each sleeve 7 is provided in front of the arm 8 with a locking cam 86, so constructed that, when the sleeve 7 is operated by pushing back the corresponding push button 2 and push bar 3, this locking cam will be thrown into the path of the pin 76 and will prevent the operation of the shaft 20 by reason of the contact of said pin with said cam when such operation is attempted.

I have hereinbefore referred to the re-setting of the machine, an operation which must be accomplished after each voter has finished voting. To effect this re-setting I utilize the shafts 20, and for this purpose each sleeve 74 secured on said shaft is provided with a second arm 87, carrying a pin 88, lying in the rear of the finger 8. It will be seen that, if the shafts 20 are rotated in a direction opposite to that in which they are rotated when utilized in voting, the pins 88 will come into contact with the backs of the fingers 8 and will return said fingers and the registering and locking mechanisms operated by them to their normal or original positions. To accomplish this result each shaft 20 is provided, at that end of the machine which lies to the left and which may be termed the operating end of the machine, with a projecting portion extending through the partition 72, and on this projecting portion is loosely mounted a sleeve 89, provided

with an arm 90, pivoted at its free end to a connecting bar 91, to which all of the arms 90 are thus pivotally connected. Each clip 84 is provided with a laterally projecting lug 92, which passes through a suitably formed slot 93 in the partition 72, said lug lying in the path of the corresponding arm 90. The connecting bar 91 is pivotally united at its lower end to an arm 93, connected with a shaft 94, which is adapted to be operated from the exterior of the casing by the re-setting lever 95. In order to permit the removal of the end of the casing 1 to give access to the working end of the machine, the connection between the lever 95 and shaft 94 is not a direct one, but said lever is connected to a shaft 96, having its bearings in the end of the casing 1 in line with the shaft 94, the two shafts being connected by a double clamp coupling 97, which carries the arm 93, as indicated in Fig. 23. It will be seen that after a voter has completed his voting the entire set of registering mechanisms and locking rods may be returned to their original or normal position, ready for the next voter, by operating the lever 95, which, through the arm 93 and connecting rod 91, will bring all of the arms 90 into contact with the projections 92 on the several shafts 20 and will operate these shafts in the manner hereinbefore described to re-set the registering mechanisms and the locking rods ready for further use.

I have shown the sleeve 7 as provided with counterbalance weights 98, secured to the locking cams 86 for the purpose of counter-balancing the locking rods and thereby insuring that the parts shall remain in whatever position they are moved to either by the operating or re-setting mechanisms.

It is desirable to provide means for registering the total number of votes cast by those entitled to complete suffrage, and for this purpose I employ a register 99, which is of any suitable construction, preferably such as that already described in connection with the shafts 6. This register is carried by a stud shaft 100, projecting inward from the partition 72, and is supported by means of a sleeve 101, having a projecting arm 102, which is connected by a link 103 with an arm 104 secured on the shaft 94. The sleeve 101 carries the pawl arm which operates the register, and the register wheels are provided with spring pins similar to those shown in Fig. 20 and are mounted on a second sleeve having a shoulder similar to the shoulder 21 and provided with a hand grasp 105, by means of which it may be turned to set the register back to zero.

So far as described, the machine is adapted for use only in voting for candidates who have been duly nominated and to whom a separate push button and register have been assigned. It is desirable, however, that pro-

vision should be made to permit the voter to vote for any person for whom he wishes to cast a ballot, irrespective of the fact as to whether he has been nominated for office.

5 In order to make provision for this, I mount at the top of the machine a shaft 106, supported in the manner hereinafter described, and on this shaft I provide a plurality of casings 107, mounted to rotate on the shaft to a limited extent, there being one of these casings in each vertical row, as shown in Figs. 1 and 1^a. Each casing is provided with a handle 108 and with a flattened portion of its circumference 109, provided with 10 a slot 110. A roll of paper 111 is mounted in the casing and extends out through the slot, being connected with a receiving roll 112, secured on a shaft 113, there being one roll for each casing. Each casing is also 15 provided with a pin 114, into the path of which extends an arm 115 on a sleeve 116, loosely mounted on a shaft 117, extending the length of the machine and mounted in the partitions 72 and 73. Secured to the 20 shaft 117 adjacent to each sleeve 116 is a collar 116^a having an arm 116^b which lies in the path of the arm 124 of the sleeve 116, hereinafter referred to. This shaft 117 has secured to it near the operating end of the 25 machine a sleeve 118, which is provided with oppositely extending arms 119 and 120. The shaft 113 has secured thereon a ratchet wheel 121, and the arm 119 has pivoted thereto a pawl 122, while the arm 120 has pivoted to it a pawl 123, both of said pawls 30 engaging with the ratchet wheel 121. Each sleeve 116 is provided with a rearwardly extending arm 124, which is secured to one of the arms of one of the locking rods 27 of 35 the vertical group in which the corresponding casing 107 is arranged. It will be observed that, in case the voter desires to vote for an independent or unnominated candidate for any given office, he may do so by 40 taking hold of the handle 108 of the casing 107 in the particular vertical row assigned to candidates for that office and pulling downward on said handle, causing the casing to rotate on the shaft 106. This will 45 cause the pin 114 to engage with the arm 115 and will rotate the sleeve 116, thus forcing the locking rod 27 downward and locking that particular group or vertical row of 50 push buttons in such a manner that none of the push buttons can be operated. This 55 rocking motion of the sleeve 116 is imparted to the shaft 117 by means of the collar 116^a and arms 116^b and 104, and rotation of this shaft causes the pawl 120 to actuate the 60 ratchet wheel 121 and thus turn the shaft 113 and the receiving rolls 112 mounted thereon. This draws the paper from the roll 111, so that, when the handle 108 is 65 pulled down, there is exposed on the flat surface 109 of the casing a blank portion of the

roll. Upon this exposed blank portion of the roll the voter may write the name of the person for whom he wishes to vote for that particular office. The re-setting of this portion of the device is accomplished in the following manner. The shaft 117 extends through the partition 72 in the same manner as the shafts 20 with which it is in vertical line, and the projecting extremity is provided with a lug 125, which lies in the path of a projection 126, secured on the sleeve 89, which is loosely mounted on the shaft 20 immediately below the shaft 117. When the re-setting lever is operated and the sleeve 89 is turned, the projection 126 will come in contact with the lug 125 and will return the shaft 117 to its normal position. This return movement of the shaft will cause the arm 116^b to engage the arm 124, and, by rotating the sleeve 116, cause the arm 115 to press upon the pin 114 and restore the casing 107 to its original or closed position. All of the independent casings which may have been pulled down are thus 90 restored to normal simultaneously. The slack of the paper caused by this return of the casing will be taken up by the action of the pawl 122, which, by its engagement with the ratchet wheel 121, will turn the shaft 113 and the reciprocating drums 112, thus 95 taking up said slack.

It will be observed that all of the receiving drums for the paper strips upon which the independent votes are recorded are actuated each time that any one of them is utilized, and it will also be noted that each of said drums is provided with one or more perforating projections 126', the said projections being arranged in a line across the machine, so that all of the paper strips for recording the independent votes for different offices are marked with a corresponding line of perforations. In case the voter, having recorded an independent vote for a given person for any one office, subsequently casts 100 an independent vote for the same person for another office, the fact that he has voted for the same person for two offices will appear when the vote is canvassed, by reason of the fact that the same name appears twice on 110 the same line, and the vote thus cast may 115 therefore be rejected.

I prefer to so mount the shaft 106 that said shaft, along with the rolls of paper and casings mounted thereon, may be readily 120 removed from the machine by a duly authorized person. To that end the shaft 106 is mounted in bearings 127 near each end of the machine, and these bearings are provided with dovetailed supporting feet 128, 125 mounted in correspondingly dovetailed ways 129, secured to the rear side of the front of the casing. Each way 129 is provided with a boss 130, apertured for the passage of a locking pin 131, and the part 128, as well as 130

the base of the way 129, are provided with corresponding apertures, all of which register when the shaft 106 is in its normal position, so that the locking pin may pass 5 down through the several parts and secure the shaft firmly in place. The feet or extensions 128 are longer than the ways 129 and are provided at their rear ends with a downwardly extending lug or projection 132, which, when the parts are unlocked in the manner hereinafter described, will permit the forward motion of the said parts and prevent the shaft 106 from being drawn 10 entirely out of the machine. The locking 15 rods 131 are pivotally connected to arms 133 on a shaft 134, extending the length of the machine and adapted to be operated from the exterior of the machine by means of a hand wheel 135. In order to permit the removal 20 of the mechanism from the casing without affecting the shaft 134 and the locking rods connected therewith, I have adopted the following construction. The end of the casing, which is indicated at 136, is provided 25 with a sleeve bearing 137, in which is mounted a shaft 138, shown in dotted lines in Fig. 22, said shaft carrying at its outer end the hand wheel 135, while its inner end is provided with an arm 139 having a projecting pin 140. The shaft 138 is in line 30 with the shaft 134, and this latter shaft is provided at its end with a plate 141, having a slot 142, into which the pin 140 extends. It will thus be seen that when the hand 35 wheel is rotated the shaft 134 will be correspondingly rotated. In order to prevent the unauthorized release and removal of the parts from the machine, I employ a lock 143, the bolt 144 of which is adapted to engage 40 with a notch 145 in the upper edge of the plate 141. This lock 143 is accessible from the exterior of the casing, as shown in Fig. 2, so that a properly authorized person 45 provided with a key may release the lock and remove the rolls of paper. The plate 141 is provided with a projection 146, which, by its contact with the lock 143, serves as a stop arm to prevent the turning of the shaft 134 too far. When the shaft 134 has been turned 50 to release the slides which carry the rolls of paper, the shaft 106 may, as hereinbefore described, be drawn forward, and the paper which has been inscribed by the voters with the names of the independent candidates, 55 and which is wound upon the rolls 112, may be drawn out and removed for inspection and to be recorded and counted. In order to permit this removal of the paper, the pawls 122 and 123 must be withdrawn from 60 contact with the ratchet wheel 121, and this is effected by providing on the shaft 134 an arm 147, which carries a link 148, pivotally connected to the arm at its upper end and slotted at its lower end, as indicated at 65 149, to receive a pin 150 on an arm 151 con-

nected to the pawl 122. A second link 152 is also pivoted at its upper end to the arm 147 and is slotted at its lower end, as indicated at 153, to receive a pin 154 on an arm 155 on the pawl 123. It will thus be 70 seen that, while these pawls are free to operate in the manner hereinbefore described, by reason of the slotted connections with said links, when the shaft 134 is turned to release the locking rods the links engage 75 with the pins on the pawl arms and lift said pawls clear of the ratchet wheel 121, so as to permit the withdrawal of the paper wound upon the rolls 112.

The apparatus is also constructed and arranged for use in presidential elections, and in practice the vertical row of push buttons at the left of the machine, or nearest what I have termed the working end thereof, is assigned to the several electoral tickets 80 each push button being assigned to the ticket of one party, so that the operation of said push button will ordinarily register on a single register a vote for each of the electors of the particular ticket to which it is assigned. It is, however, desirable that provision should be made to permit the voter to vote a "split" ticket for electors, or, in other words, to vote for only a portion of the electors of a given ticket, filling out the number 90 for which he is entitled to vote by any other names of his choice. To this end I provide, immediately to the left of the first row of push buttons, an opening in the front of the frame or casing, in which is mounted a 100 separate auxiliary frame 156, secured in position in the manner hereinafter described, and supporting a vertical row of casings 157, similar in their general construction to the casings 107. Each casing is mounted on a 105 shaft 158 and consists of a cylindrical body portion 159, a handle 160 and a flattened surface 161, provided with a slot 162. A roll of paper, indicated at 163, is mounted on the shaft 158 and extends through the 110 slot 162, being carried to and wound around a receiving roll 164, mounted loosely on the shaft 6. There is connected to this roll 164 in such a manner as to rotate therewith a ratchet wheel 165, which is operated by 115 pawls 166 and 167, pivoted to the body of the casing 157 in such a way that one of the pawls will operate the ratchet wheel when the casing is rotated in one direction, while the other pawl will operate the ratchet wheel 120 when the casing is rotated in the opposite direction. Each of the first row of push buttons is so constructed that the sleeve 7 carrying the arm 8 co-operating therewith is elongated, as indicated at 168, so that it extends to a point adjacent to the roll 164 on the corresponding shaft 6. This sleeve extension is provided with an arm 169, carrying a rod 170, which extends across the strip 125 of paper 163 immediately adjacent to the 130

point where it issues from the slot 162 when the casing 157 is in normal position, and said rod 170 is provided with pins or points 171, as shown in Figs. 5 and 7, which points are 5 adapted to perforate the paper for the purpose hereinafter set forth. The sleeve extension 168 also carries a second arm 172, provided with a stop pin 173. The casing 157 is provided with a curved stop flange 174, the curvature being such as to permit 10 the pin 173 to move freely when the sleeve extension 168 is operated, while at the same time the pin 173 when in its normal position, as shown in Fig. 7, will prevent the casing 157 from being operated.

Assuming that the voter desires to vote a "split" electoral ticket, he proceeds as follows. He first presses the push button of the first vertical row of buttons which 20 corresponds with the party whose electoral ticket he in the main desires to vote. This operation not only registers a vote for that ticket and locks the other electoral push buttons, but also serves to so turn the sleeve 25 extension 168 as to raise the pins 171 clear of the paper 163, and also raise the stop pin 173 to a position which will permit the turning of the casing 157. Said casing is then grasped by the handle 160 and turned 30 downward so as to expose the flat surface 161 thereof. This motion at the same time causes the pawl 167 to feed the roll 164 forward, thus drawing the ticket last voted out of sight. The voter then writes upon the 35 portion of the paper thus exposed the name of the elector for whom he desires to vote, and this may be done in any way which will serve to designate not only the person for whom he wishes to vote as such elector, but 40 also the person regularly nominated as a candidate for elector on that particular ticket for whom he does not wish to vote and for whom he desires to substitute the person whose name he writes upon the paper strip. 45 This is preferably accomplished by indicating the electoral ticket upon the face of the machine and assigning to each regularly nominated candidate a number, so that, when the independent voter writes upon the 50 strip the name of his candidate for elector, he can at the same time add the number of the particular elector for whom he does not wish to vote.

If the voter wishes to vote for more than 55 one electoral candidate not on the regular ticket, he raises the handle 160 and lowers it again, and during this movement the pawls 166 and 167 will feed the paper strip forward, so as to expose a fresh portion 60 thereof, upon which the voter may record his vote in the manner just described. This operation may be repeated as often as desired, and when the voter has completed his voting and the machine is re-set, the pin 173, 65 by its contact with the stop flange 174, will

return the casing 157 to its normal position, if it has not already been so returned by the voter, and this return movement will, through the pawl 166, again rotate the roll holder 164 and take up the slack of the paper 163. At the same time the arm 169 will descend, forcing the pins 171 through the paper at a point which will indicate the end of the portion exposed to the voter when he wrote the names of his candidates thereon. It will thus be seen that, in case the voter votes for a number of electors greater than the number for which he is entitled to vote, a scrutiny of the number of names between the two sets of perforations will indicate this fact, and also indicate that this particular vote is to be rejected on that account. In order to prevent the voter from operating the straight ticket mechanism and then subsequently operating the mechanism 70 just described for voting a "split" electoral ticket, I provide each shaft 20 with an arm 175, having a flange 176, which, when the shaft 20 is so rotated as to operate the registering mechanisms, will descend into the 75 path of the corresponding pawl 167, and, by its contact with the end of said pawl, will prevent the casing 157 from being operated. The auxiliary frame 156 which carries the several casings 157 is secured in position in 80 the main frame in the following manner. The frame 156 is provided at the top and bottom with rearwardly extending arms 176 and 177. Above said frame there is mounted on the inner surface of the front wall of 85 the main frame 1 a bracket 178, having an apertured boss 179, and the arm 176 is similarly apertured for the passage of a locking rod 180, pivoted to an arm 181, secured to the shaft 134. The rearwardly extending 90 arm 176 is provided with an upwardly extending projection 182, which, by its contact with the bracket 178, prevents the frame from being withdrawn entirely from the 95 casing. Below the frame 156 there is secured on the inner surface of the front wall of the machine a bracket 183, having an apertured boss 184 for the passage of a locking rod 185, also pivoted to the arm 181. The arm 177 has a stop projection 186 corresponding in its functions with the stop 100 projection 182, and said arm is suitably apertured for the passage of the locking rod 185. It will be thus seen that, when the shaft 134 is turned in the proper direction 105 in the manner hereinbefore described, the locking rods 180 and 185 will be disengaged from the arms 176 and 177, and, so far as these locking devices are concerned, the frame is free to be drawn out to give access 110 to the rolls of paper wound upon the roll holders 164.

The machine is also so organized as to permit of a referendum vote, or, in other words, a "yes" or "no" vote for or against 115

any proposition or propositions submitted to the voters. The lowermost row of push buttons is employed for this purpose, said push buttons being combined by suitable controlling mechanism in groups of two, each group being assigned to the vote on any given proposition, and the arrangement being such that if one of the buttons of a group is used the other button is locked out and cannot be used. The push buttons are constructed and operated in the manner already described, and in connection with each push button there is employed a register 187, similar in construction to the registers already described and mounted on a normally fixed shaft 188, corresponding in general with the shafts 6. The sleeve 189 mounted on this shaft adjacent to the register carries the register operating pawls and is provided with an arm 190, which projects into the path of the corresponding push button. This sleeve also carries an arm 191, to which is pivoted a locking rod 192 by means of a pivot pin 193. The body of the locking rod 192 is preferably jointed, as indicated at 194, the axis of the joint being at right angles to the pivot pin 193. The pivot pins 193 of the two mechanisms of each group extend toward each other, and one of them is preferably elongated so as to bring the two locking rods side by side, as shown in Fig. 16. The bed piece 32 is provided with a groove or race way 195, in which are arranged a plurality of balls or spheres 196, and the locking rods are provided with wedge-shaped portions 197 and reduced extensions 198, as in the case of the locking rods 27. The bed piece 32 is also provided with an aperture 199, through which the ends of the locking rods 192 extend. Each group of registers and locking rods has coöperating with it a section of the groove 195, which is cut off from the remaining sections of the groove by a suitable partition or dividing means, which are permanent when the machine is in use. In the present instance the rods 36 constitute these dividing means as they pass through the groove 195, but this is a mere matter of convenience, and other dividing means may be employed. The balls of each section of the groove are of such a size and number that when one of the locking rods 195 has been depressed by the operation of its corresponding push button and register, so that the broader portion thereof passes down between the balls, the space in that particular section of the groove is filled, so that the other locking rod cannot be depressed. It will thus be seen that when the voter votes either "yes" or "no" on any proposition submitted he cannot also vote on the other side of the same proposition. The register operating means are re-set and the locking rods released by providing on

the shaft 94 a series of arms 200, each carrying a pin 201, which, when the shaft 94 is turned to re-set the machine, will come into contact with the arms 190 and restore the parts to their normal position.

70

It is frequently the case that at an election some of the voters are entitled to vote for a limited number of candidates only, as, for instance, where women are allowed to vote for school officers. I have made special provision for adapting the machine for use where limited suffrage of this character exists. This mechanism is as follows. Near the lower end of each rod 27 there is formed thereon a shoulder 202, and adjacent to these shoulders there extends the length of the machine a shaft 203, supported in bearings in the partitions 72 and 73, in which bearings it is adapted to rock. Upon this shaft there are secured a plurality of sleeves 204, 80 preferably corresponding in number with the vertical rows of push buttons, or, in other words, with the number of offices to be filled. Each sleeve 204 is provided with two stop shoulders 205 and 206, adapted, under 90 the proper circumstances, to be so turned as to engage with the shoulders 202 of the locking rods 27. The sleeves 204 are adjustable around the shaft 203, and said shaft is capable of being rocked in its bearings by means, 95 hereinafter described, accessible from the exterior of the casing of the machine. Now it will be seen that, if one or more of the sleeves 204 are set back in the manner shown more particularly in Fig. 8, the shaft 203 100 may be so turned that the shoulders 205 of all of the sleeves, except that one or those set back, will be in the path of the shoulders 202 of the locking rods 27. It results from this that when the shaft 203 is turned or 105 rocked in the manner just described, none of the locking rods 27 can be depressed except those belonging to that group or those groups of which the corresponding sleeves have been set back in the manner just described. Consequently, assuming that a person entitled to limited suffrage only desires to vote, the shaft 203 is turned in the manner described, so as to lock all portions of the voting mechanism except those particular parts thereof which are assigned to those candidates for which the person having a limited suffrage is entitled to vote.

110

115

The mechanism whereby the shaft 203 is operated is as follows. Said shaft extends 120 through the partition 72 at the working end of the machine and is provided at its end with an arm 207, which is connected by means of a link 208 with an arm 209 on a sleeve 210, mounted on a shaft 125 211. The sleeve 210 is provided with a projection 212, which lies in the path of a pin 213, secured on an arm 214, which is in turn secured on a shaft 215, which extends through the casing and is provided on the 130

outside thereof with an operating lever 216. By turning the lever 216 in the direction indicated by the arrow in Fig. 2^a, the pin 213 is caused to engage the lug 212 and thus, 5 through the medium of the arms 209 and link 208, move the rock shaft 203 in the desired direction. In order to insure that the rock shaft shall be moved to the proper extent to lock out the proper locking rods 21 10 and leave the proper ones unlocked, the shaft 203 is provided at its end with a stop arm 217, in the path of which is arranged a stop projection 218, consisting of the bolt of a lock 219, mounted on the inner face of the 15 end of the casing and accessible for the exterior thereof, the key hole being indicated at 220. After the limited suffrage voter has voted the parts are returned to their normal position by the following mechanism. A link 221, pivoted at its upper end 20 to the arm 93, is pivoted at its lower end to an arm 222, mounted loosely on the shaft 211 and provided with a projection 223, in the path of which lies a projection 224 on the arm 209. When the operating lever 95 is turned to re-set the machine the projection 223 comes into contact with the projection 224 and turns the sleeve 210, and by the medium of the link 208 and arm 207 turns 25 the shaft 203 to its original or normal position. The shaft 211 serves in itself as a locking out device for the referendum vote mechanism, said shaft being extended through the machine and being provided 30 with a flattened side 225, which, when the parts are in the normal position, will permit the locking rods 192 to pass downward, as indicated in Fig. 10. Said shaft is also provided with a shoulder 226, which, when 35 the shaft is turned into position to permit a limited suffrage voter to vote, lies in the path of the lower ends of the locking rods 192 and prevents downward motion of these rods and, consequently, any operation of the 40 referendum vote push buttons or registering mechanism. The re-setting of the machine by means of the lever 95 returns the shaft 211 to its normal position in the manner already described and thus leaves the referendum mechanism free to be operated. The 45 shaft 203 also provides a means for locking the machine at the close of an election, so that it can no longer be operated in any of its parts. This is accomplished by without 50 drawing the bolt 218 of the lock 219 out of the path of the arm 217, whereupon the lever 216 may be swung clear over until the arm 217 has passed the bolt 218. The bolt 218 may then be again moved down into the 55 path of the arm 217, thus preventing the return of the parts. When this operation has been accomplished the shaft 203 is turned 60 into such a position that the projections 204 of those sleeves 204 thereon which have not 65 been set back will be in line with the shoul-

ders 202 of the corresponding locking rods and will therefore prevent any operation of any of these rods. At the same time the projections 205 of those of the sleeves 204 which have been set back also come in line 70 with the shoulders of the corresponding rods and prevent their depression, so that all of the rods 27 are positively locked from movement. At the same time the projection 224 is brought up against the projection 223, 75 thereby locking the shaft 94 and operating lever 95 from movement. By this means the entire machine may be locked after the vote is cast without any access being had to its interior and may be transported if necessary 80 in this condition to a suitable place where its registers may be inspected and a record of their showing made.

It is desirable that a separate record be kept of the total number of votes cast by 85 those entitled to limited suffrage only, and for this purpose I employ a suitable register 227, similar in structure and mode of mounting to the register 99, and operated by a link 228 from an arm 229 on the shaft 203. 90

I have deemed it desirable that an audible signal be provided for the purpose of indicating when the levers 95 and 216 are operated. For this purpose I employ in connection with the lever 95 a bell 230, mounted 95 on the outer side of the partition 72.

231 indicates a stud shaft, on which is mounted a sleeve 232, carrying a resilient striker arm 233, having a striker 234. The sleeve 232 is also provided with an arm 235, to which is connected one end of a coiled spring 236, the other end of which is connected with a fixed pin 237 on the partition 72. A fixed stud 238 forms a stop against which an arm 239 of the sleeve 232 is held by 100 the spring 236, in the normal position of the parts. This arm 239 is provided with two extending fingers 240 and 241. Two of the arms 90 above and below the arm 239 are provided respectively with projecting pins 110 242 and 243, in the path of which the arm 239 lies. When the lever 95 is moved downward the pin 242 comes in contact with the finger 240 and swings the lever 232 around on its pivot until the point of connection 115 of the spring 236 with the arm 235 has passed the line connecting the stud shaft 231 with the pin 237, whereupon the force of the spring will turn the sleeve 232 until one of the lugs 244 to which the striker 120 arm 233 is attached comes into contact with the stop pin 238. In this position of the parts the finger 241 lies in the path of the travel of the pin 243, and upon the return or upward stroke of the lever 95, said pin will 125 contact with said arm and will turn the sleeve until the point of connection of the spring 236 with the arm 235 has passed the line connecting the pin 237 and stud shaft 232, whereupon the spring will throw the 130

sleeve over the remainder of its travel, bringing the arm 239 against the stop 238 and causing the striker 234 to strike the bell and then rebound clear of the same. Thus 5 each time that the main operating lever is operated to re-set the machine an audible signal is given. In connection with the lever 216 I employ a bell 245, mounted on the partition 72 in a manner similar to the mounting 10 of the bell 230, and in connection with this bell 245 I employ a striker 246, mounted on a resilient striker arm 247, carried by a sleeve 248, mounted on a stud shaft projecting from the partition 72. This sleeve is 15 provided with an arm 249, having a pin 250, which is connected by a coiled spring 251 with a fixed pin 252 on the partition. In the normal position of the parts the striker arm 207 is held against a stop 253 by the 20 spring 251, said striker arm being secured to the sleeve 248 between lugs 254. The sleeve 248 is provided with an arm 255, and the shaft 203 has an arm 256 provided with a pin 257, in the path of which the arm 255 25 lies.

258 indicates a stop pin in the path of the upper lug 254. When the lever 216 is operated downward the arm 256 moves upward and strikes the lower lug 254, rotating the 30 sleeve 248 until the pin 250 has passed the line of the centers of the stud shaft on which the sleeve 248 is mounted on the pin 252, whereupon the spring 251 rotates the said sleeve until the upper lug 254 strikes 35 the stop pin 258, whereupon the resiliency of the arm 247 will permit the striker 246 to strike the bell 245 and rebound therefrom. Upon a return movement of the lever the pin 257 will act on the arm 255 and return 40 the parts to their normal position. It will thus be noted that the bell operated by the limited suffrage lever rings during the first or upward movement of that lever, thus indicating that the machine is set for a limited 45 suffrage vote, while the bell connected with the resetting lever 95 rings during the upward motion of said lever after the completion of its work and indicates that the machine is re-set for the next voter.

50 Access may be had to the interior of the casing at the back so as to adjust the sliding carriages 49 and its stop device, and also to adjust the sleeves 204 and loosen the double clamp 97 by means of a sliding 55 panel 259, adapted to move longitudinally in ways 260 and normally held locked by means of a bolt 261 forming part of a lock 262, secured on the inner face of the end of the casing and accessible from the 60 exterior thereof through a key hole 263, so that an authorized person having the proper key can have access to the interior of the structure for the purposes mentioned. The front of the casing is provided with eight 65 apertures 264, one in front of each register,

and between these apertures and extending longitudinally of the machine are guide strips 265, forming between them ways or grooves in which are placed sheet metal strips 266, lying back of strips of glass or 70 other transparent material 267, held in place in the grooves by thin metal strips 268, of greater width than the guide strips 265. The sheet metal strips carry cards or other printed matter relative to the push buttons 75 adjacent to which they are located, such, for example, as the name of the candidate, the office which he seeks, and the name of the party to which he belongs. These sheet metal strips serve not only as indicators, but 80 also serve to close the sight openings 264 in such a way that the registers cannot be seen. The strips 266 are held in place by means of studs 269, carried by a plate 270, secured to or formed on the frame 156, said studs passing through apertures 271 in the ends of the strips. When the voting is completed, the frame 156 being released and drawn forward in the manner hereinbefore described, the studs 269 are disengaged from the apertures 90 271 in the strips 266, and these latter may then be withdrawn through slots 272 in the end plate at the opposite end of the machine, thus permitting the inspection of the registers. The plate 270 may be provided in any 95 suitable manner with the emblem and name of the party to which each particular horizontal line of push buttons is assigned. Similarly, the casings 107 and 157 may be provided with tickets 265' or otherwise inscribed with suitable instructions indicating the manner of their use. The space to the left of the straight vote levers 77 is provided with suitable tickets 266', covered by glass or the like and held in place by metallic 100 strips 267', said cards or tickets containing instructions as to the use of the straight vote levers. The partitions 72 and 73 in connection with the tubular cross piece 28 and bed piece 32 constitute an inner frame which is 110 inclosed within the outer casing and which supports all of the mechanism except the operating levers and other devices secured to the end of the main casing. This frame is secured to the front of the casing by means 115 of screw bolts 273. The ends and front and back are secured together by screw bolts 274, and when it is desired to inspect the mechanism the screw bolts connecting the front with the ends may be unscrewed, 120 whereupon the entire front, together with the secondary frame just described, may be drawn out of the casing, thus giving access to all parts of the machine. It will be understood that the machine will be in charge 125 of a suitable attendant or official who can attend to the operation of the levers 95 and 216, and who, after the vote is completed, can lock up the machine if necessary in the manner already described. After the regis- 130

ters have been inspected and the number of votes indicated by them has been recorded the registers can be readily set back to zero by turning the shafts on which they are mounted. As already pointed out, the registers indicating the total number of votes cast and total number of limited suffrage votes cast are provided with special hand wheels whereby they may be turned back to zero. The shafts 6 and 188 are provided with a slot 275, into which a suitable tool, such as a screw driver, may be inserted, thereby turning back these shafts and setting all of the indicators back to zero in the manner already described. In order to prevent longitudinal movement of these shafts, their projecting ends, which extend through the partitions 72 and 73, are provided with collars 276 thereon. In order to permit the re-setting of the registers without removing the mechanism from the casing, the end 136 of the casing is provided with a series of apertures 277, in line with the ends of the shafts 6 and 188, and also preferably with a sleeve 278 extending inward from each aperture. Each aperture is normally closed by a screw plug 279, which may be removed in order to permit the insertion of the re-setting tool. In order to prevent unauthorized re-setting of the registers, I employ a locking strip 280, extending over the inner ends of all of the sleeves 278 and being capable of being moved longitudinally. This locking strip is provided with apertures 281, and when the strip is so moved that these apertures register with the sleeves 278 the re-setting tool may then be inserted and the shafts turned back. When the blank or non-apertured portions of the locking strip register with the sleeves 278, access cannot be had to the end of the register shafts. As a convenient mode of mounting this locking strip, I support it upon lugs 282, against which it is frictionally held by screws 283, passing through slots 284 in the strip. When access is had, by a properly authorized person, to the interior of the casing by opening the slide 259, the locking strip may be so moved as to permit the registers to be re-set. The normal position of the locking strip, however, is such as to prevent access to the register shafts from the exterior of the casing. While the roll casings may be constructed in any suitable manner, I prefer the detailed construction shown, in which the handle portion of each casing consists of a body portion 285, having a recess 286 to receive the ticket 265'. Secured to this handle portion and extending around the same is a sheet metal cover 287, having a sight opening 288, of smaller dimensions than the recess 286, said sheet metal covering having a slot 289 through which the ticket may be introduced into the recess. The casing is provided with

end portions 290, and the covering 287 extends partially around these end portions, receiving an opening 291 at the bottom, through which the paper roll may be introduced into the casing.

The several locks hereinbefore referred to may be of any suitable description, but I prefer to employ locks of the type known as "safety deposit" locks, which can only be opened by the use of two different keys, so that the custody of these keys may be given to different persons, thus requiring the action of both of them in order to have access to the interior of the machine.

It is obvious that portions of my invention may be embodied in a machine of the class to which it relates without necessarily embodying all of the novel features enumerated. It is also obvious that various modifications in the details of construction and arrangements of the parts may be made without departing from the principle of my invention. For instance, although I have described the re-setting and limited suffrage levers as being hand operated by an attendant, it is obvious that they might be operated through suitable connections by means of doors or turnstiles, as is common in machines of this character. I therefore do not wish to be understood as limiting myself strictly to the precise details hereinbefore described and shown in the accompanying drawing.

Having thus fully described my invention, what I claim as new, and desire to secure by Letters Patent, is:

1. A voting machine comprising registers for each candidate, said registers being arranged in office and party rows, operating mechanism and an actuator for each register, interlocking mechanism for each office row, a plurality of shafts each coöperating with the corresponding party row, an actuator accessible to the voter for each shaft, whereby said shaft may be operated in one direction to actuate all of the register operating mechanisms of that row, and means for operating said shaft in the opposite direction to re-set all of the register operating mechanisms of said row, substantially as described.

2. A voting machine comprising registers for each candidate, said registers being arranged in office and party rows, operating mechanism and an actuator for each register, interlocking mechanism for each office row, and a plurality of shafts, one coöperating with each party row, an actuator accessible to the voter for each shaft to operate the same in one direction to actuate all of the register operating mechanisms of that row, and means for simultaneously operating all of said shafts in the opposite direction to re-set all of the registers, substantially as described.

3. A voting machine comprising registers for each candidate arranged in office and party rows, actuating mechanism for each register comprising a projecting arm, an actuator for each register comprising a movable part adapted to engage said arm and move it in one direction only, whereby the operating mechanism is actuated, and a plurality of shafts, one for each party row, each shaft provided with two arms for each register operating mechanism, one arm adapted to engage the projecting arm of the operating mechanism to actuate it in one direction, and the other arm adapted to engage it when the shaft is moved in the opposite direction to re-set the register, an actuating device for each shaft accessible to the voter to operate the shaft in the first-named direction, and means for simultaneously operating all of the shafts in the opposite direction to re-set all of the register operating mechanisms, substantially as described.

4. In a voting machine, a push button provided with a stem, in combination with a register and an operating mechanism therefor having a projecting arm arranged in the path of the stem and a locking segment adjacent thereto, a shaft having means controlled by the voter for rocking it in one direction and other means for rocking it in the opposite direction, said shaft being provided with arms which engage the projecting arm of the register operating mechanism on opposite sides thereof to give said operating mechanism an actuating or re-setting movement, substantially as described.

5. A voting machine, comprising registers for each candidate, arranged in office and party rows, operating mechanism and an actuator for each register, interlocking mechanism for each office row, and a straight vote shaft for each party row adapted to be actuated by the voter and to in turn actuate all of the registers of its row, each register operating mechanism being provided with a locking out device, whereby when any one register of a party row is operated the party shaft of that row is locked, substantially as described.

6. In a voting machine, comprising registers for each candidate, arranged in office and party rows, and means for operating each register, of an interlocking mechanism for each office row comprising a limited race way having balls therein, and a group of inverted U-shaped rods suitably guided at their upper ends, each rod having one of its lower ends connected with one of the register operating mechanisms and its other lower end wedge shaped and adapted to enter the race way, substantially as described.

7. In a voting machine, the combination, with the registers and their operating mechanism, of a locking rod for each register, a

continuous race way into which the ends of the locking rods are adapted to enter, balls located in said race way, and transversely movable abutments sub-dividing said race way, each abutment comprising a non-yielding portion and a ball, either of which may be brought into alinement with the race way by the transverse movement of the abutment, substantially as described. 70

8. In a voting machine, the combination, with the registers and their operating mechanism, of a locking rod for each register, a continuous race way into which the ends of the locking rods are adapted to enter, balls located in said race way, transversely movable abutments sub-dividing said race way, each abutment comprising a non-yielding portion and a ball, either of which may be brought into alinement with the race way by the transverse movement of the abutment, 80 and a stop adapted to be inserted in the race way at any desired point, substantially as described. 85

9. In a voting machine, the combination, with the registers and their operating mechanism, of a locking rod for each register, a continuous race way into which the ends of the locking rods are adapted to enter, balls located in said race way, transversely movable abutments subdividing said race way, 90 each abutment comprising a non-yielding portion and a ball, either of which may be brought into alinement with the race way by the transverse movement of the abutment, and a carriage longitudinally movable parallel with the race way and provided with a stop adapted to be inserted in the race way, 95 substantially as described. 100

10. In a voting machine, the combination, with the registers and their operating mechanism, a bed piece provided with a race way having balls located therein and locking rods, one for each register, the ends of which are adapted to enter said race way, of a carriage longitudinally movable along said bed piece 105 and adapted to be secured thereon in any desired position, and a shaft mounted in said carriage and provided with an arm which may be turned down into the race way to form a stop, said carriage being provided with means for clamping said shaft, 110 substantially as described. 115

11. In a voting machine, the combination, with the registers, their operating mechanism, and a locking rod for each register, of a locking device comprising a bed piece provided with a race way into which the ends of the locking rods are adapted to enter, balls in said race way, and a dovetail way parallel with the race way, a carriage fitting 120 said dovetail way and provided with a split bearing, a shaft mounted in said split bearing and having a stop arm which may be turned into the race way, a bolt having a block fitting the dovetail way and extend- 125 130

ing through the split bearing, and a clamping nut fitting said bolt and adapted to simultaneously clamp the carriage to the ways, and clamp the split bearing on the shaft, 5 substantially as described.

12. In a voting machine, the combination, with the registers, their operating mechanism, and a locking rod for each register, of a locking device comprising a bed piece having a longitudinal race way into which the ends of the locking rods are adapted to enter balls in said race way, a plurality of transverse apertures intersecting the race way, and a divided rod for each aperture 10 having a ball located between its inner ends and having its outer ends connected by a yoke, said rods being longitudinally movable, substantially as described.

13. In a voting machine, the combination, with the registers, their operating mechanism, and a locking rod for each register, of a locking device comprising a bed piece having a longitudinal race way into which the ends of the locking rods are adapted to enter, 20 balls in said race way, and transverse apertures intersecting the said race way, a longitudinally movable divided rod in each aperture having a ball between its inner ends and having its outer ends connected by a 25 yoke, and means for securing said yoke and rod after adjustment, substantially as described.

14. In a voting machine, the combination, with the registers, their operating mechanism, and a locking rod for each register, of a locking device comprising a bed piece having a longitudinal race way into which the ends of the locking rods are adapted to enter, 30 balls in said race way, and transverse apertures intersecting the said race way, a longitudinally movable divided rod in each aperture having a ball between its inner ends and having its outer ends connected by a yoke, 35 and means for securing said yoke and rod after adjustment, comprising a fixed pin on the bed piece, and a clamp carried by the yoke and embracing said fixed pin, substantially as described.

15. In a voting machine, the combination, 40 with registers for each candidate for a given office arranged in a row, of operating mechanism for each register, an actuator for each operating mechanism adapted to impart to it a single movement in one direction, an independent voting device in the same row comprising a casing having a roll of paper, a receiving roll, intermediate mechanism whereby the moving of the casing into voting position imparts a single 45 feeding movement to the receiving roll, and re-setting mechanism whereby the register operating mechanisms and the intermediate feeding mechanism of the independent voting device are all simultaneously re-set into

5 position to be again operated by their actuating devices, substantially as described.

16. In a voting machine, the combination, with registers for each candidate for a given office arranged in a row, of operating mechanism for each register, an actuator for each 60 operating mechanism adapted to impart to it a single movement in one direction, an independent voting device in the same row comprising a casing having a roll of paper, a receiving roll, intermediate mechanism 65 whereby the moving of the casing into voting position imparts a single feeding movement to the receiving roll, re-setting mechanism whereby the register operating mechanisms and the intermediate feeding mechanism of the independent voting device are all simultaneously re-set into position to be 70 again operated by their actuating devices, and interlocking devices whereby the operation of any one register or the independent 75 voting device locks the remainder of the row, substantially as described.

17. In a voting machine, the combination, with registers for each candidate arranged in office and party rows, of independent voting mechanism comprising a row of independent voting devices, one for each office 80 row, each device comprising an oscillating casing having a roll of paper therein and a receiving roll, a shaft on which said receiving 85 rolls are secured, a second shaft parallel therewith, a plurality of sleeves on said second shaft, one for each casing, each sleeve provided with an arm adapted to be engaged by the casing and with a second arm, 90 said second shaft having rigid therewith adjacent to each sleeve a projection lying in the path of the second arm of the sleeve, a ratchet wheel on the receiving roll shaft, 95 and pawls carried by the parallel shaft and adapted to operate the receiving roll shaft, 100 substantially as described.

18. In a voting machine, the combination, with registers for each candidate arranged in office and party rows, of independent voting mechanism comprising a row of independent voting devices, one for each office 105 row, each device comprising an oscillating casing having a roll of paper therein and a receiving roll, a shaft on which said receiving rolls are secured, a second shaft parallel therewith, a plurality of sleeves on said second shaft, one for each casing, each sleeve provided with an arm adapted to be engaged by the casing and with a second arm, 110 said second shaft having rigid therewith adjacent to each sleeve a projection lying in the path of the second arm of the sleeve, a ratchet wheel on the receiving roll shaft, 115 and pawls carried by the parallel shaft and adapted to operate the receiving roll shaft, 120 said second arm of the sleeve being connected with an interlocking mechanism common 125

to all the registers of the office row, substantially as described.

19. In a voting machine, the combination, with registers for each candidate arranged in office and party rows, actuating mechanism for each register, and interlocking devices for each office row, of an independent voting mechanism comprising a plurality of oscillating casings each provided with a roll of paper and having a projection, a corresponding plurality of receiving rolls secured on a common shaft, a rock shaft parallel with said receiving roll shaft, a plurality of sleeves loosely mounted on said rock shaft, each sleeve provided with an arm lying in the path of the projection of the corresponding casing and with a second arm connected with the interlocking mechanism of the first row, said rock shaft having rigid therewith projections lying in the paths of said second sleeve arms, a ratchet wheel on the receiving roll shaft, pawls connected with the rock shaft to impart a feeding movement to said receiving roll shaft at each movement of the rock shaft, the operation of any one casing actuating said rock shaft in one direction, and a re-setting mechanism actuating said rock shaft in the opposite direction, substantially as described.

20. In a voting machine, the combination, with registers for each candidate arranged in office and party rows, of an operating mechanism for each register, means for independently actuating each operating mechanism, a plurality of shafts, one for each party row, and provided with means for actuating all of the register operating mechanisms of that row independently of the individual actuating means thereof, and actuating mechanism for each shaft comprising a lever, a link pivotally connected therewith at one end and slotted at the other end, and an arm secured to the shaft and provided with a pin engaging the slot of the link, substantially as described.

21. In a voting machine, the combination, with a register for each electoral ticket, of operating mechanism for each register, interlocking mechanism for the several register operating mechanisms, and independent voting devices, one for each register operating mechanism and interlocked therewith, whereby when any one register is operated the corresponding independent voting device is unlocked and made accessible to the voter, said independent voting device being provided with means for indicating the voter's choice, substantially as described.

22. In a voting machine, the combination, with a register for each electoral ticket, of operating mechanism for each register, interlocking mechanism for the several operating mechanisms, and independent voting devices, one for each register operating

mechanism and interlocked therewith, each voting device comprising an oscillating casing adapted to receive a paper roll, a receiving roll, and feeding mechanism whereby the receiving roll is operated by the movement of the casing, substantially as described.

23. In a voting machine, the combination, with an electoral register and an operating mechanism therefor, of an independent voting device comprising an oscillating casing having a paper roll and a receiving roll operated thereby, a locking device for locking the independent voting device until the electoral register is operated, re-setting mechanism, and a marking device operated by the re-setting mechanism and adapted to indicate on the paper the portion exposed between each two re-setting movements, substantially as described.

24. In a voting machine, the combination, with an electoral register and operating mechanism therefor, of an independent voting device comprising an oscillating casing having a paper roll, and a receiving roll operated thereby, a locking device for locking the independent voting device until the electoral register is operated, re-setting mechanism, a marking device actuated by the re-setting mechanism and provided with points which are forced through the paper to perforate the same when the re-setting mechanism acts, said marking device being connected with the register operating mechanism so as to be withdrawn from the paper when the register is operated, substantially as described.

25. In a voting machine, the combination, with an electoral register, of operating mechanism therefor comprising an oscillatory sleeve, said sleeve being provided with a stop arm and with a second arm provided with paper puncturing devices, in combination with an independent voting device comprising a casing adapted to contain a roll of paper and having a stop flange lying in the path of the stop arm, and a receiving roll actuated by the movements of the casing, an actuator for the register adapted to move said sleeve in one direction and thereby withdraw the perforating devices and move the stop arm out of the path of the stop flange, and re-setting mechanism adapted to move said sleeve in the opposite direction, whereby the stop arm, by its contact with the stop flange, returns the casing to its normal position, and whereby the perforating devices are forced through the paper just exposed, substantially as described.

26. In a voting machine, the combination, with registers for each candidate arranged in office and party rows, and similarly arranged electoral registers, of operating mechanism for each register, straight vote mechanism for actuating all of the registers

of each party row, including the electoral register, interlocking devices for each office row and for the electoral row, independent voting devices, one for each electoral register operating mechanism and interlocked therewith, so that the operation of an electoral register releases the corresponding independent voting device, and interlocking means between said independent voting device and the corresponding straight vote mechanism, whereby when the latter is operated the former is locked, substantially as described.

27. In a voting machine, the combination, with registers arranged in party rows, operating mechanism for each register, and a straight voting shaft provided with actuating means and having a stop arm thereon, of an independent electoral voting device comprising an oscillatory casing containing a paper roll, a receiving roll provided with a ratchet wheel, and a pawl pivoted to the casing and adapted to engage the ratchet wheel, the stop arm of the straight voting shaft lying in the path of said pawl when said shaft is operated, to cast a straight ballot, substantially as described.

28. In a voting machine, the combination, with an electoral register and operating mechanism therefor, of an actuator and re-setting mechanism for said operating mechanism, an independent voting device interlocked with said operating mechanism and comprising an oscillatory casing adapted to receive a paper roll, and a receiving roll operated by said casing, whereby when said register operating mechanism is actuated the independent voting device is free to be repeatedly operated, and a marking device actuated by the re-setting mechanism and adapted to indicate upon the paper the portion thereof exposed while the independent voting device is unlocked, substantially as described.

29. In a voting machine, a referendum voting mechanism comprising a shaft having registers arranged thereon in pairs, an operating mechanism for each register comprising an actuator, a sleeve provided with an arm located in the path of the actuator and having a second arm, a locking rod pivotally depending from said second arm and jointed to move laterally at its lower end, and a race way adapted to receive said locking rods, having balls therein, and subdivided by fixed abutments into groups corresponding to the number of pairs of registers, substantially as described.

30. In a voting machine, the combination, with registers for each candidate arranged in office groups and provided with similarly arranged locking rods, each having a shoulder, of a rock shaft having a plurality of sleeves mounted on and independently adjustable around the same, each sleeve being

provided with a shoulder adapted, when said sleeve is suitably adjusted and the rock shaft is actuated, to lie in the path of the shoulders of the corresponding group of locking rods, substantially as described. 70

31. In a voting machine, candidate registers and operating mechanisms arranged in groups, each group provided with a corresponding group of shouldered locking rods, and a rock shaft having a corresponding plurality of sleeves mounted on and independently adjustable around the same, each sleeve being provided with two shoulders, whereby when said rock shaft is partially operated the more advanced shoulders of the preadjusted sleeves lie in the path of the corresponding groups of operating rods and lock the same, the other groups being free to operate, and whereby when the rock shaft is further rotated the succeeding shoulders of the first-mentioned sleeves and more advanced shoulders of the remaining sleeves lie in the path of and lock all the locking rods, and means accessible from the exterior of the machine for locking the rock shaft in this last-mentioned position, substantially as described. 80 85 90

32. In a voting machine, candidate registers and operating mechanisms arranged in groups, each group provided with a corresponding group of shouldered locking rods, and a rock shaft having a corresponding plurality of sleeves mounted on and independently adjustable around the same, each sleeve being provided with two shoulders, whereby when said rock shaft is partially operated the more advanced shoulders of the preadjusted sleeves lie in the path of the corresponding groups of operating rods and lock the same, the other groups being free to operate, and whereby when the rock shaft is further rotated the succeeding shoulders of the first-mentioned sleeves and more advanced shoulders of the remaining sleeves lie in the path of and lock all the locking rods, and means accessible from the exterior of the machine for locking the rock shaft in this last-mentioned position, substantially as described. 95 100 105 110

33. In a voting machine, the combination, with their registers and their operating mechanism arranged in rows, and each operating mechanism having a projecting arm, of re-setting mechanism comprising a plurality of shafts corresponding in numbers 120 to the rows of registers, each shaft being provided with an arm to engage the corresponding arm of the register operating mechanism to re-set the same, each shaft having at one end a projection secured there- 125 130

on, and a sleeve loosely mounted on said shaft and provided with an arm in the path of which the projection lies, a bar connecting all of said last-mentioned arms, and a lever operatively connected with said bar to simultaneously actuate all of the shafts and re-set all of the register operating mechanisms, substantially as described.

34. In a voting machine, the combination, 10 with registers and operating mechanisms arranged in office rows, of a visible signal for each row, connecting mechanism whereby when any register of a row is operated the signal of that row will be displayed, a second visible signal, and connecting mechanism whereby when any one of the first-mentioned signals is displayed said second signal will also be displayed, substantially as described.

20 35. In a voting machine, the combination, with registers and operating mechanisms grouped in office rows, each group being provided with a corresponding group of locking rods of inverted U-shape, of a visible signal 25 for each row comprising a lever having a signal at one end and having at its other end a rod of a length equal to the length of one group of locking rods and arranged between the arms of the rods of said group, 30 and a second visible signal comprising a rock shaft having an arm provided with a signal, and a plurality of arms, one of which extends under the rod of the signal lever of each group of locking rods, substantially as 35 described.

36. In a voting machine, the combination, with register supporting shafts adapted by their rotation to turn the registers to zero, of a main casing having openings in line 40 with the ends of the shafts, a longitudinally movable strip normally closing said openings and having apertures which may be caused to register therewith to give access to the shafts, said strip being located within 45 the main casing, and said main casing being provided with a door controlled by a lock to give access to the strip, substantially as described.

37. In a voting machine, the combination, 50 with vote recording mechanisms, of actuators adapted to operate said mechanisms, but not positively connected therewith, whereby when an actuator is once operated further operation thereof is ineffective until 55 the machine is reset, interlocking mechanisms for interlocking said vote recording mechanisms in office groups, and resetting mechanism adapted to directly reset the voting mechanisms independently of the interlocking mechanisms, but not positively connected 60 with the voting mechanisms, substantially as described.

38. In a voting machine, the combination, 65 with a main casing, of voting mechanism mounted in a separate frame removable from

the casing, and actuating levers mounted on the exterior of the casing, having short shafts extending through the casing into the interior thereof and provided with separable connections with the coöperating parts of the voting mechanism which they are designed to operate, substantially as described.

39. In a voting machine, a voting mechanism comprising registers, a main casing having sight openings for each register, non-transparent strips adapted to slide in ways in the main frame to close said sight openings, an auxiliary frame sliding in the main frame and provided with studs to engage the said strips and hold them in position, and means for locking said auxiliary frame in position in the main frame, substantially as described.

40. In a voting machine, the combination, with a voting mechanism comprising registers, of a main frame having sight openings for said registers and provided with ways or grooves, sheet metal strips adapted to be slid into said ways or grooves to close the sight openings and provided with suitable legends, means for locking said sheet metal strips in position in said ways, and transparent strips of glass or the like lying in said grooves or ways outside of said sheet metal strips, substantially as described.

41. In a voting machine, the combination, with registers for each candidate arranged in office and party rows, means for operating each register, and a plurality of interlocking devices arranged in a given plane, of an abutment or stop adjustable into and out of the path of said interlocking devices and also adjustable parallel with the plane thereof.

42. In a voting machine, the combination, with the registers for each candidate arranged in office and party rows, means for operating each register, and a longitudinally disposed way having interlocking mechanism therein, of an arm movable parallel with the length of said way and adapted to move into said way to form a stop.

43. The combination in a voting machine of a plurality of voting keys arranged in party rows, a rock shaft for the voting keys of each party row and loosely connected thereto, each of said voting keys being operable to voted position independently of the other voting keys, and means for simultaneously operating all of said shafts in the reverse direction to reset the voting keys.

44. The combination in a voting machine of a plurality of voting devices arranged in party rows, a rock shaft for the voting devices of each party row connected thereto, an actuator accessible to the voter for each shaft to operate the same and place all the voting devices connected thereto in voted position, and means for simultaneously operating all of said shafts in the reverse direction to reset the voting devices.

45. The combination in a voting machine of a plurality of voting devices arranged in party rows, a rock shaft for the voting devices of each party row, and connected thereto, an actuator accessible to the voter for each shaft to operate the same and place all the voting devices connected thereto in voted position, and means for simultaneously operating all of said shafts in the reverse direction to reset the voting devices, each of said voting devices being operable to voted position independent of the other voting devices and independent of the rock shaft connected thereto.
- 10 46. The combination in a voting machine of a plurality of voting devices arranged in a row, a rock shaft arranged parallel to said

row of voting devices, said rock shaft being loosely connected to each one of said voting devices, a straight ticket key connected to 20 said rock shaft whereby it may be operated to simultaneously place all the voting devices connected thereto in voted position, resetting mechanism connected to said shaft, whereby it may be operated on the resetting 25 of the machine to reset the voting devices connected thereto.

In testimony whereof, I affix my signature in presence of two witnesses.

ELMER E. WOLF.
